ATTORNEY.

UNITED STATES PATENT OFFICE.

ROBERT A. JENCKES, OF PROVIDENCE, RHODE ISLAND, ASSIGNOR TO GENERAL FIRE EXTINGUISHER COMPANY, OF NEW YORK, N. Y., A CORPORATION OF NEW YORK.

SUPPORT FOR PIPE-HANGERS.

941,714.

Specification of Letters Patent. Patented Nov. 30, 1909.

Application filed March 5, 1906. Serial No. 304,211.

To all whom it may concern:

Be it known that I, ROBERT A. JENCKES, of the city and county of Providence and State of Rhode Island, have invented certain new and useful Supports for Pipe-Hangers; and I do hereby declare the following specification, taken in connection with the accompanying drawings, forming a part of the same, to be a full, clear, and exact description thereof.

In the construction of modern buildings the floors and walls are frequently made of concrete, cement, or the like, built or formed upon false wood work, which false wood work, when the concrete or similar material is set, is removed. The plaster is applied directly to the concrete or similar material.

My invention relates to a support or anchor for pipe hangers which are particularly adapted for use in floors and walls constructed in the above manner. Heretofore the practice has been to drill a hole in the solid concrete and insert an expansion bolt, which expansion bolt is provided with suitable means for securing the pipe hanger thereto. Such method is difficult and expensive, requiring much labor, and the cost of the expansion bolts employed is considerable.

The object of my invention is to provide a suitable support which will overcome the objections to the supports heretofore used, and which will also furnish a more rigid and satisfactory support for the pipes to be suspended therefrom.

To that end the invention consists of an anchor or support adapted to be placed in position before the concrete or cement is applied, and so as to be embedded and held in the concrete or cement when the same becomes set.

Referring to the drawings, Figure 1 is a side elevation of my improved support or anchor supported in the false wood work prior to the application of the concrete. Fig. 2 is a corresponding view after the concrete has been applied. Fig. 3 is a corresponding view showing the false wood work removed. Fig. 4 is a sectional view on the line $x-x$, Fig. 6. Fig. 5 is a sectional view on the line $y-y$, Fig. 6. Fig. 6 is a side elevation of my improved support or anchor

showing the ceiling complete with the plaster supplied and the pipe-hanger in place in said support.

The anchor or socket which may be cast or otherwise formed of any suitable metal, comprises a body portion 1 and a projecting portion or neck 2. The body portion is provided with a flanged head 3 which serves to support the anchor when embedded in the concrete against downward pull. Preferably the neck portion 2 is of somewhat reduced diameter so as to form another flange 4 at the lower end of the body portion. If desired the body portion 1 may be made solid and the flange 3 be made to project therefrom. It is preferred, however, to make the body portion of webbed construction, and so as to form the webs or ribs 5 as shown in the drawings and particularly in cross section in Fig. 4, as thereby the amount of metal may be considerably lessened and at the same time pockets or recesses will be formed into which the concrete or cement can enter and so that the support or anchor will be more firmly and securely held in place in the concrete. With this web construction also the webs or ribs 5 serve to prevent the support or anchor from turning, as for instance when the pipe-hanger is being screwed therein. If desired the body portion 1 may be cylindrical in shape, but it is preferred to make the same tapering or of frusto-conical shape, as shown, as this construction serves to still further hold the support or anchor against downward pull.

The projecting neck portion 2 is tapped with a screw thread, so that the end of the pipe-hanger 6 may be screwed therein.

The manner of applying the support or anchor is as follows: A hole is bored in the false wood work 7, and the neck 2 of the support is inserted in this hole, and so that the support or anchor will be properly located and held in position for the application of the concrete, as shown in Fig. 1.

Fig. 2 shows the concrete 8 applied upon the false wood work with the anchor embedded therein and with the false wood work still in position. After the concrete or cement has become hardened and set the false wood work is removed, leaving the neck portion 2 of the anchor projecting

below the concrete, as shown in Fig. 3. The plaster 9 is then applied to the concrete, as shown in Fig. 6.

Preferably the neck portion 2 is made of 5 such length that after the plaster has been applied, said neck portion will project somewhat below the lower surface of the plaster, as shown in Fig. 6, as such construction will guard against the liability of 10 the neck portion being buried in or covered by the plaster and against the liability of the hole tapped therein for the reception of the hanger rod being filled with plaster. It will be evident, however, that said neck 15 portion 2 need only be of sufficient length to properly support the anchor in the false work while the concrete is being applied. It is also evident that if said neck portion were not of sufficient length to project below 20 the plaster, the liability of said neck portion being covered by or the hole therein filled with plaster can be prevented by simply inserting the hanger rod in place in said neck portion before the plaster is 25 applied.

In order to support the anchor in proper vertical position while the concrete is being applied it is desirable that the neck portion 2 should fit the hole formed for its reception in the false wood work comparatively snug. It has been found that under the action of the moisture in the concrete there was a liability of the wood work swelling and gripping this neck portion to such 30 an extent as to make it difficult to remove the false wood work. To guard against this difficulty the neck portion 2 is preferably provided with projecting ribs 10. With this construction the wood work will be in con-

tact only with the comparatively narrow 40 outer surfaces of these projections, and the effect of the gripping action will be correspondingly reduced, and so that the wood work may be readily removed, even if swollen by the moisture. 45

By the use of an anchor or socket like that above described, a pipe hanger support is provided which may be conveniently secured in position and at comparatively little expense, while at the same time the device furnishes a firm and rigid support for the pipe-hanger and the pipe carried thereby. 50

What I claim as my invention and desire to secure by Letters Patent is:

1. An anchor or support adapted to be 55 embedded in plastic material comprising a body-portion and a neck-portion, said neck-portion being provided with spacing ribs or projections, substantially as described.

2. An anchor or support adapted to be 60 embedded in plastic material comprising a body-portion provided with flanges with intermediate webs or ribs connecting said flanges, and a neck-portion provided with spacing ribs or projections, substantially as 65 described.

3. An anchor or support adapted to be embedded in plastic material comprising a frusto-conical body-portion provided with flanges and with intermediate webs or ribs 70 connecting said flanges, and a neck portion provided with spacing ribs or projections, substantially as described.

ROBERT A. JENCKES.
